UNITED STATES PATENT OFFICE.

HIRAM W. WHITE, OF YANKTON, DAKOTA TERRITORY.

GUN-STOCK.

SPECIFICATION forming part of Letters Patent No. 247,451, dated September 20, 1881.

Application filed September 16, 1880. (No model.)

To all whom it may concern:

Be it known that I, HIRAM W. WHITE, of Yankton, Dakota Territory, have invented certain new and useful Improvements in Gun-Stocks, of which the following is a specification.

The invention relates to that class of stock-butts which are adjustably connected with the gun-stock, whereby they may be projected therefrom or retracted thereto more or less to regulate the length of the stock in accordance with the length of the gunner's arm, and also, when the connection of the butt with the stock is elastic, to regulate the degree of this elasticity to suit the firing of light or heavy charges.

My invention consists in the special form of the stock-butt, and the special manner of elastically and adjustably connecting the same with the stock, as hereinafter fully set forth.

The figure in the drawing presents a side elevation of a gun-stock, shown in section at the butt end, where my improvement is applied.

The gun-stock is indicated by *a*, and is made in about the usual form, except at the butt, where the opposite sides are preferably made parallel for a short distance, as shown, to better receive the yielding butt.

b indicates the butt of the stock, which is made of the usual appropriate shape to fit against the arm or shoulder, and according to this invention is adjustably and elastically connected with the stock. This butt-piece *b* is preferably made of thin sheet or cast metal, in cupped shape, to fit upon and slide over the end of the stock, being formed with a projecting rim, say from one to two inches deep, which loosely embraces the end of the stock, as shown, and is capable of sliding back or forth thereon in a straight and steady manner. The butt is formed with an inwardly-projecting thimble or socket, *c*, at or about its middle, in which the head end of a long screw, *d*, lies, while the threaded end screws into the wood of the stock or into a metal nut embedded in the stock. From the outer ends of the butt two parallel pins, *e*, project into guide-holes *f* in the stock, and around these guide-pins are placed strong spiral springs *g*, which are socketed in the guide-holes *f*, resting at their lower ends upon the bottom of the holes, while they press at their outer ends against the butt *b* with a constant tendency to project the butt

from the stock as far as the adjustment of the screw *d* will allow.

It will now be seen that the connection of the butt with the stock is elastic by reason of the interposed springs *g*, so that the gun rests against the shoulder upon a yielding butt, the elasticity of which causes the shock of the recoil in firing to be cushioned upon the shoulder; thus rendering it but slightly perceptible, and enabling constant firing to be done without distress. At the same time the degree of elasticity may be adjusted by turning the screw *d* in or out, so as to suit the strength of the gunner or the weight of the gun and the strength of the charges fired therefrom, as may be desired.

It may also be seen that the adjustment of the butt in or out by turning the screw *d* will also regulate the length of the stock as may be required to better suit the length of the gunner's arm, which is an important advantage, as this enables the gun to be grasped and commanded with greater ease and accuracy, and for this purpose the interposed springs *g* may or may not be used.

It may be observed that the form of the springs between the stock and the butt is immaterial, as they may be spiral or flat, or made of metal or rubber, and one, two, or any other suitable number of springs may be used. Thus one central spring may be arranged around the socket instead of having two springs around the guide-pins *e*, which latter may in this case fit the guide-holes *f* snugly.

Another advantage of the construction shown is that, as the yielding butt is guided on the stock so as to yield in a straight line parallel with the gun-barrel, there is hence no tendency to raise or tilt the muzzle, and thus detract from the accuracy of the aim at the instant of firing, as is likely to be the case where the butt is hinged at one end to the stock and elastically connected at the opposite end, as is the case in a previous form of elastic butt.

I do not, of course, wish to infer any broad claim to merely an elastic or yielding stock-butt, whether connected with the stock by a hinge-joint or by parallel guide-pins, with a device to adjust the butt to or from the stock, as I am aware that several previous instances of such may be cited in addition to the one

just referred to. In my invention, however, the special form of the butt and its arrangement relatively to the stock is novel, as is also the adjusting-screw *d*, which works through the butt and engages with the stock, and is accessible for adjustment from the end of the butt, which has the advantages of simplicity, convenience, and efficiency.

What I claim is—

- 10 The combination, with a gun-stock bored with the two parallel guide-holes *ff*, of the

yielding butt *b*, connected with the stock by the adjusting-screw *d*, and provided with the two parallel guide-pins *e e*, encircled by the cylindrical spiral springs *g*, both socketed and guided in the said guide-holes, substantially as and for the purpose set forth. 15

HIRAM W. WHITE.
